Attorney

UNITED STATES PATENT OFFICE

JOSEPH MESSING, OF PHILADELPHIA, PENNSYLVANIA

LATCH NEEDLE

Application filed May 25, 1930. Serial No. 365,813.

My invention relates to improvements in a knitting needle adapted for repairing knitted fabric and particularly adapted for repairing runs in stockings.

5 The object of my invention is to provide novel means upon the needle for better performing the different steps in the operation of repairing the fabric by forming the straight, or raveled, threads into the loops 10 and interlooping the adjacent threads, thus mending, or restoring the fabric to its original form; a further object is to provide means upon the needle for separating a straight thread, or a tight thread, from a looped 15 thread, by which means the straight thread will be prevented from moving with the looped thread over the top of the latch and from being discharged over the hook instead of into the hook of the needle, thus dropping 20 the stitch, or loop, and necessitating starting the looping of the threads again at the beginning of the run in the fabric, thereby involving a great loss of time. My present invention insures the entrance of the straight 25 thread into the hook of the needle before the latch closes upon the hook, thus forming a perfect stitch and permitting the needle to be operated very rapidly, either manually or mechanically. In carrying out my invention 30 I provide a bifurcated latch, having furcations, or forks, thereof terminating at different distances from the pivot point of the latch. I also employ an enlarged part upon the shank of the needle for guarding the 35 longer fork of the latch from engagement with a thread passing over the shank when the latch is in the open position, and said enlarged part of the shank being so formed and located upon the shank that it will retard the 40 movement of a looped thread in its passage over the shank towards the open position of the latch and the hook, thus allowing the straight thread to advance faster toward the hook and engage the shorter fork, or prong, 45 of the latch and move the latch into a position in which the longer fork will be engaged by said looped thread.

This arrangement insures the straight thread entering the hook of the needle and 50 said looped thread being discharged over the

latch and the hook, thereby forming a perfect stitch or loop. These together with various other novel features of construction and arrangement of the parts, which will be more fully hereinafter described and claimed, 55 constitute my invention.

Referring to the accompanying drawing, Fig. 1 is a side elevation of my improved needle, showing the latch in the closed position, and drawn on a greatly enlarged scale; 60 Fig. 2 is a front or edge view of Fig. 1; Fig. 3 is a view similar to Fig. 1, partly in section, and showing the latch in the open position; Fig. 4 is a front or edge view of Fig. 3; Fig. 5 is a side elevation of the needle illustrating 65 the first step in the operation of the needle to form loops in the fabric; and Figs. 6 to 10 are views similar to Fig. 5 showing the latch in the different positions assumed throughout the various steps of the operation of the 70 needle during the formation of one complete loop in the fabric.

In the accompanying drawing, in which like reference characters refer to like parts, 75 1 represents a needle comprising a shank 2, having a hook 3 formed thereon. Said hook is provided with a point 5 located in spaced relation with the shank 2, thus forming a throat 6 for the free entrance of a thread between the point 5 of the hook and the shank. 80 The opposite end 7 of the shank 2, relatively to the hook, is shown provided with means for operating the needle such as a handle 8.

The shank 2 is provided with an enlarged portion forming cheek pieces 10, between 85 which is formed a slot 12, in which is pivotally mounted a latch 14. At the inner end of said latch is provided means such as the shaft 15, for mounting the latch in the bearings formed by the cheek pieces 10.

The latch 14 is constructed with a bifurcated free end portion comprising a long fork 16 and a shorter fork, or prong 18. Between said forks is formed a notch 20 adapted for receiving a thread. The longer fork 16 extends slightly beyond the point 5 of the hook 3 and the shorter prong 18 terminates adjacent to the point of the hook when the latch is closed upon the hook, as shown in Fig. 1, whereby the opening or notch 20, communi- 100

cates with the throat 6 of the hook and the shorter fork, or prong 18 extends into the throat 6 of the hook, as the prong 18 is located on the side or edge of the latch which 5 engages the point 5 of the hook. The cheek pieces 10 extend a sufficient distance in the opposite direction from the hook 3 to allow the longer fork 16 to occupy the slot 12 between the cheek pieces 10 when the latch is in 10 the open position, as shown in Figs. 3, 4, 7 and 8, whereby the cheek pieces 10 form a guard 21 adapted for preventing a thread moving over the guard 21 from engaging the longer fork 16 of the latch. When the latch 15 is in the open position, as shown in Figs. 3, 4, 7 and 8, the shorter fork, or prong 18, projects beyond the cheek pieces 10, and also beyond the guard 21, so that it may be engaged by a thread moving over the guard 21 and the cheek pieces 10. Said shorter fork, 20 or prong 18 is inclined away from the point 5 of the hook when the latch is in the open position, thus allowing a thread to pass freely over the fork, or prong 18, when moving 25 away from the hook and insuring the engagement of the fork, or prong 18 by a thread moving over the shank toward the hook. When the shorter fork, or prong 18 is engaged by a straight thread *a* entering the 30 notch 20 formed in the bifurcated end portion of the latch, as shown in Figs. 8 and 9, the thread *a* will move the latch about the pivot shaft 15 and withdraw the longer fork 16 from the slot 12 formed in the shank and expose said longer fork 16, above the guard 21, 35 as shown in Fig. 9.

The looped thread *b* as it continues to move over the shank toward the hook 3 will engage the fork 16 and close the latch upon the hook 3, as shown in Fig. 10, during which operation the straight thread *a* will be directed into the throat 6 of the hook by the longer fork 16.

A novel means is shown for separating the straight thread *a* from the looped thread *b* when the needle is being withdrawn from the fabric, as indicated by the arrows, Figs. 8 to 10. Said means consists of an inclined surface, or cam, 22 formed upon the shank 45 at the opposite end of the cheek pieces 10 relatively to the hook 3. The cam 22 extends obliquely from the wide portion of the shank forming the guard 21 toward the upper portion 7 of the shank which is of smaller cross-sectional area above the cam 22 than the 50 cross-sectional area including the guard 21 or the cheek pieces 10. Said cam 22 is located a sufficient distance above the point of the longer fork 16 of the latch, when in 55 the open position, shown in Figs. 3, 7 and 8, to form means for retarding the movement of the looped thread *b* before said looped thread *b* is moved over the cam 22 to a position embracing the point of the fork 16. By 60 retarding the looped thread *b* in its passage

over the cam 22 toward the fork 16, the straight thread *a* will move faster than the looped thread *b* toward the hook 3 and engage the prong 18 of the latch and rotate the latch so as to expose the longer fork 16 beyond the guard 21, in which exposed position the longer fork 16 will be engaged by the looped thread *b* when it moves over the guard 21 toward the hook 3. 70

It will be understood that the straight 75 thread *a* will move freely over the cam surface 22 and over the guard 21 and that the thread *b* which is looped around the shank will have to be stretched sufficiently to allow it to pass over the cam 22, thus retarding the movement of the looped thread *b* sufficiently 80 to allow the straight thread *a* to advance beyond the cam 22 and operate the latch into a position in which the fork 16 will be engaged by the looped thread *b*. The straight thread *a* will assume a position in the notch 20 between the forks 16 and 18 and it will be carried by the latch in advance of the longer fork 16, which latter will direct the straight thread 85 *a* into the throat 6 of the hook. 90

The operation of my invention is as follows; the hook 3 as shown in Fig. 5, is inserted into the first one of the loops *b* and *b'*, of the fabric, which is to be knitted or interlooped with the straight threads *a* and *a'*, which have become disengaged from each other, or raveled. When the needle is advanced downwardly through the fabric from the position shown in Fig. 5 to the position shown in Fig. 6, as indicated by the arrows, 100 the looped thread *b* or a straight thread *a* open the latch and move the latch into the full open position, shown in Fig. 7, with the looped thread *b* positioned upon the reduced portion 7 of the shank above the cam 22. The movement of the needle is now reversed, 105 as shown by the arrow in Fig. 8, and as it is drawn upwardly through the fabric, the loop *b* will slide down the shank to the cam 22 where it will be retarded by said cam. The straight thread *a* is free to move relatively 110 to the cam 22 and the guard 21 and will therefore move in advance of the looped thread *b*, which must be stretched by the cam 22 before the needle can pass through said loop *b*. 115

The straight thread *a* will engage the fork or prong 18 of the latch before the looped thread *b* rides completely over the cam 22. A further upward movement of the needle will cause the straight thread *a* to rotate the latch thus moving the longer fork 16 from the slot formed in the guard 21, into the position shown in Fig. 9, in advance of the looped thread *b*, which latter will follow the fork 16 and as the needle is further withdrawn 120 from the position shown in Fig. 9 to that shown in Fig. 10, the looped thread *b* closes the latch upon the hook and the longer fork 16 directs the straight thread into the throat 6 of the hook. From the position shown in 125 130

Fig. 10 the needle may be withdrawn through the loop *b* and the straight thread will be retained within the hook and become the second loop, and the beginning of the second operation.

5 Various changes in the construction and the operation of my needle may be made, such as operating the needle by a suitable machine, instead of using a handle as herein illustrated, without departing from my invention.

10 I claim:—

A mending needle comprising a shank having a hook, a latch pivoted on the shank, said latch having a free end portion adapted to 15 engage the hook when in the closed position, a guard upon the shank located adjacent to said free end portion of the latch when in the open position adapted to prevent said free end portion of the latch from being engaged 20 by a thread passing over the shank, a prong upon the latch located between said free end portion of the latch and the hook when the latch is in the open position, said prong located adjacent to the free end of the latch 25 and projecting above the guard when the latch is in the open position, said guard forming an enlargement upon the shank, covering one-half the length of the latch when the latter is positioned at right angles to the 30 length of the shank and forming means for retarding the movement of a looped thread toward the hook relatively to the movement of a straight thread whereby the straight thread will engage said prong and move the 35 point of the latch into the path of the looped thread.

In testimony whereof I affix my signature.
JOSEPH MESSING.
